UNITED STATES PATENT OFFICE

SILL WOYCHESKIN, OF MARLIN, TEXAS

PLOW

Application filed June 7, 1929. Serial No. 369,190.

This invention relates to new and useful improvements in plows and has more particular reference to certain improvements in attachments or appliances for expediting 5 the work and rendering the structure more susceptible to fulfilling the requirements of a structure of this kind in a more satisfactory manner.

The invention has more particular reference to the type of plow including a beam 10 having a down-turned standard especially constructed to accommodate novel accessories for promoting more accurate and dependable adjustment of the plow sweep or shovel.

One feature of construction is predicated upon the utilization of a new type of landside which is attached to the lower end of the standard and provided with an individually adjustable runner or shoe, in order 20 to promote rigidity and to withstand rough usage even in abrasive sand and the like.

A further feature of the invention is the sweep stock which is associated with the standard in a manner to permit it to be arranged at the desired angle with respect to the line of draft, and to be elevated vertically for different features of plowing.

Still another object and feature is predicated upon the use of adjustable handle structures which is capable of adjustment at desired elevations to render it easy to handle by both short and tall operators.

Then too, the structure is further defined by a novel coupling or connector device between the handles which are pivotally and adjustably mounted on the standard and pivotally connected with the sweep stock to assist in raising it up and down.

A prominent and readily distinguishable feature is found in the employment of a vertically disposed upright which is carried by the landside and disposed in spaced parallelism to the main standard to provide anchorage for an adjacent end of the stock as well as anchorage for the intermediate portion of the connector which exists between the handles and said stock.

Other objects, features and advantages

will become more readily apparent from the following description and drawings.

In the drawings:—

Figure 1 is a side elevational view of a complete plow constructed in accordance 55 with the invention showing the general association of parts.

Fig. 2 is a top plan view of the same.

Fig. 3 is a vertical section on the line 3—3 60 of Fig. 1.

Fig. 4 is a detail section on the line 4—4 of Fig. 1.

Fig. 5 is a perspective view of the upright.

Fig. 6 is a perspective view of the landside, and

Fig. 7 is a view of the connection between the ground engaging sweep and the attaching stock.

Referring now to the drawings by reference numerals, it will be seen that 8 designates generally the plow shaft which includes the customary beam 9 of ordinary configuration, having a downturned standard 10. This standard is distinguishable in that it includes a vertical row of adjusting holes 11 and has a widened head 12 at its lower end. This head is bolted to the upper edge portion of a horizontal and laterally disposed landside 13. This slide is the form of a runner or furrow plate. Mounted thereon is a segmental shaped shoe 14 having pivotal connection as at 15 and having an arcuate slot 16 with which adjusting screws 17 cooperate to permit it to be adjusted around the pivot in a limited arc.

Disposed between the shoe and the standard, and rising from the landside is an upright 18 in the form of a vertically disposed flat strip or bar having a multiplicity of vertical adjusting holes 19. This has a double function as will be hereinafter seen.

The reference characters 20 designate the customary handles and 21 the braces between the beam and handle. The stock is generally designated by the reference character 22, somewhat in the form of a yoke. Referring to Fig. 7 at this time, it will be seen that the sweep is indicated at 23 and includes a heel 100

bolt 24 which is fastened between the spaced portions 25 of the stock.

These spaced portions of the stock are provided with a spacing bolt as at 26 and they straddle and extend beyond the rear edge of the standard 10. Then too, there is a bolt as at 27 which has adjustable connection with the holes 19. This point of adjustment is of a collective variety, permitting each end of the yoke to be raised up and down in turn raising the sweep higher or lower as the case may be.

The sweep is supported by a pivotal connection 28 from the adjacent end portion 15 of a specially designed connecting device 29 which exists between the stock and the handle 20. This device 29 is shaped to cooperate with the standard 10, as well as with the upright 18. In fact, it has adjustable connection with the upright as at 30 and adjustable and pivotal connection with the holes 11 of the standard 10 as at 31.

The following advantages will be notable with this improved construction. The adjustable connection between the handles and the standards of the beam structure, and the means whereby this connection may be simultaneously adjusted upon the standard as well as the upright, and firmly locked in position, is a distinguishable structural feature. This arrangement allows the handle to be elevated to any desirable plane to suit the convenience of plowmen of different statures.

38 The adjustable connection between the connector device and the upright, can be used to prevent the change of elevation from the handles from affecting the depth of running of the plow in the ground.

40 Another facility is due to the peculiar arrangement of the perforations in the standards and uprights, and the fact of the stock being largely independent of the beam, is that the beam can be lowered with respect to 45 the general angle and adjustment of the other parts, so that the plow can be run at a depth suitable for plowing at points known as sweeps of all sizes. It can also be run in the same way as the kind of plow 50 called "middle burster."

The stock is so shaped and set as to permit a middle burster point to be attached. Thus, the plow is not dependent upon the changes of the pin in the buckhead at the 55 end of the beam for making it run deeper or shallower, like other plows known to me. The adjustment must be such as to prevent the parts from being thrown out of balance and rendering the structure unwieldy.

60 I also wish to call attention to the fact that the connection between the standard 10 and the landslide 13 is near the upper edge of the landslide to permit considerable wearing of the slide before the standard ever 65 comes into rubbing contact with the ground.

It is thought that persons skilled in the art to which the invention relates will be able to obtain a clear understanding of the construction, arrangement, and features and advantages, after reading the description in connection with the drawings. Therefore a more lengthy description is believed to be unnecessary.

Minor changes in shape, size, and rearrangement of details, coming within the field of invention claimed may be resorted to in actual practice if desired.

Having thus described my invention, what I claim as new is:—

1. In a plow construction of the class described, a beam having a downturned standard at its rear end, a landside connected to and extending rearwardly at right angles from the lower end portion of said standard, an upright connected with said landside and rising vertically therefrom in spaced parallelism to said standard, said standard and said upright having vertically spaced parallel openings, a stock constructed to accommodate a ground engaging implement, said stock having its rear end portion embracing said standard and provided with a bolt for adjustable position in the openings in said upright, a handle structure, a connecting member between the handle structure and the intermediate portion of the said stock, said connecting member having a bolt intermediate its ends for adjustable position in the openings of said standard and also provided with a bolt at its rear portion for adjustable position in the openings in said upright. 90

2. In a plow construction of the class described, a beam having a downturned standard, a landside connected with and extending rearwardly from said standard, a shoe adjustably mounted on said landside,

an upright connected with and rising vertically from said landside and disposed in spaced parallelism with said standard, said standard and said upright having vertically spaced parallel openings, a ground engaging implement stock of general U-shaped form having its arm portions embracing said standard and extending rearwardly beyond said standard and having a bolt for adjustable position in the openings of the upright, handles, and a connecting member between the handles and intermediate portions of said stock, said connecting member having a bolt intermediate its ends for adjustable position in the openings in said standard and also having a bolt for adjustable position in the openings of said upright. 110

In testimony whereof I affix my signature.

SILL WOYCHESHIN.
